UNITED STATES PATENT OFFICE.

ROBERT P. FRYE, OF MARLBORO, MASSACHUSETTS, ASSIGNOR TO UNITED SHOE MACHINERY CORPORATION, OF PATERSON, NEW JERSEY, A CORPORATION OF NEW JERSEY.

MACHINE FOR REMOVING SURPLUS MATERIAL FROM BOOTS AND SHOES.

Application filed February 21, 1924. Serial No. 694,265.

This invention relates to machines for removing surplus material from boots or shoes. The invention is illustrated as embodied in a machine designed to remove from the toe 5 portions of unfinished boots or shoes the surplus material which results from the pulling-over and lasting operations. It is to be understood, however, that machines constructed in accordance with the present invention may be employed for removing surplus material from other portions of boots and shoes.

The toe portion of a shoe upper usually comprises the leather of the upper, the lining, and a toe stiffener or toe box. In modern commercial practice the toe box, which is inserted between the upper and lining before the toe lasting operation, commonly consists of a layer or layers of felt or woven 20 fabric impregnated with a mineral wax, such as asphaltum, or a compound containing such wax. Such a toe box is stiff and hard at ordinary temperatures but when moderately hot, that is, at a temperature which is 25 not injurious to leather, it is plastic and readily conformable by the lasting machine to the shape of the toe. When the margins of the upper and hot toe box are forced inwardly over the bottom of the insole, they 30 are crimped and bunched and some of the toe box wax or gum is apt to ooze out and cling to the bunched stock. In view of the foregoing conditions it is an object of this invention to provide an improved machine 35 especially adapted for removing surplus crimped and bunched upper materials from around the toes of boots and shoes in the pulling-over and lasting operations which machine will be so constructed as to obviate 40 any tendency of the more or less sticky materials removed or of the wax itself to cling to the material removing device, and which will at the same time adequately dispose of the waste material removed.

To this end the machine illustrated as embodying the invention in a preferred form comprises a hollow, rotary shell provided with projections or teeth arranged in lines parallel to the axis of the shell and having, 45 as illustrated, square, convex scraping edges, said edges lying in radial planes of the shell. Each of the illustrated projections is substantially a quarter section of a hollow 50 sphere, one edge of which is attached to or

integral with the shell, the other edge of 55 which forms the scraping edge above defined. In front of each projection is an opening extending beneath and forwardly beyond the cutting edge of the projection, the opening being sufficiently large to allow 60 free passage to the interior of the shell of the material removed by the projections. As illustrated, no dimension of the opening is substantially less than the length of the 65 scraping edge of the adjacent projection.

The material which is removed by the edges of the projections, and which passes freely through the openings adjacent to the projections, consists of particles of leather and fabric mixed with toe box wax. This 70 fibrous and cementitious material is forced through the openings by subsequently removed material in the form of lumps which tend to adhere to the inner surface of the shell not only by reason of their more or less 75 plastic and sticky character but also because of the centrifugal force produced by the rotating shell.

A further feature of the invention consists in mechanical means between which 80 and the shell there is relative movement for detaching the lumps of material from the interior surface of the shell. As shown, a scraper having an edge located adjacent to the inner surface of the shell is mounted 85 upon a shaft coaxial with the shell. The said shaft may be stationary or may be rotated in a direction reverse to the direction of rotation of the shell. One end of the shell is preferably open and the scraper may have 90 its edge next to the shell inclined to the direction of the axis of the shell so as to cause the material removed from the shell to be transferred toward its open end and to 95 be discharged therefrom.

These and other features of the invention will appear more fully from the following detailed description when read in connection with the accompanying drawing and will be pointed out in the appended claims.

In the drawing,

Fig. 1 is a side elevation of a machine partly broken away embodying the present invention, and

Fig. 2 is a perspective view of the shell 105 partly broken away to show the scraper.

In the drawing, the numeral 2 indicates a standard upon which is a bearing 4 through

which passes a shaft 6. Upon the shaft 6 is a sleeve 8 having at one end a flange 10 and at the other a pulley 12 to which power is applied by a belt 14. A cylindrical shell 16 has an open outer end and a wall 18 at its inner end which wall has an opening to receive the shaft 6, said wall being secured by screws 20 to the flange 10. A collar 22 on the shaft 6 enters the opening in the end 10 wall of the shell and abuts against the flange 10 to prevent outward endwise movement of the sleeve 8 and shell 16.

The portion of the shaft 6 which is inside the shell has secured to it a collar 24 by a screw 25. The collar is provided with an angularly arranged slot 26 in which is secured one edge of a scraper plate 28. The outer edge of the plate 28 lies in close proximity to the inner surface of the shell 16 and acts as a scraper to remove material from the inner surface of the shell. The outer edge of the plate 28 is arranged at an inclination to the axis of rotation of the shell 16, its inner end being directed backwardly and its outer end forwardly with respect to the direction of rotation of the shell, so that it acts to propel the removed material toward the open end of the shell.

The shaft 6 may be extended beyond the bearing 4 and provided with a pulley 30 arranged to be driven in a direction opposite to the direction of rotation of the shell 16 by a belt 32. This arrangement not only increases the scraping effect of the plate 28 but also enhances its action as a fan to create a current of air inwardly through openings 34 in the shell and out through the open end of the shell. If desired, the pulley 30 may be dispensed with and a set screw 36 tightened to hold the shaft 6 in the bearing 2 and prevent rotation of the scraper plate 28.

The shell 16 is provided with parallel rows of openings 34 and at one side of each opening, which side will be the following side 45 with respect to the direction in which the shell is to be rotated, there is an outward projection 38 which is substantially quarter-spherical in form. At one edge the projection is attached to or formed integral with 50 the shell 16, its other edge 40 forming an arched or outwardly convex scraping edge which is a continuation of the edge of the opening 34 of the shell. Each edge is strongly supported by the arched material 55 of the projection back of it and may be sharpened by grinding if desired. Since, as illustrated, the edge faces of the projections are square, that is, they lie in radial planes of the shell, the grinding operation is greatly 60 facilitated since it is done on the flat edge faces and not on the convex faces of the projections. The openings 34 are shown (Fig. 1) as rectangular; their shape, however, is 65 immaterial except that they should be sufficiently large to allow the material removed

by the scraping edges to pass into the shell. Adequate openings are provided if, as illustrated, no dimension of the openings is substantially less than the length of the adjacent scraping edge.

In use the shell 16 is rapidly rotated by power, the scraper 28 being either held stationary or rotated in the reverse direction. The operator presents the bottom of the toe portion of a lasted shoe, before the outsole is 70 attached, to the shell, the projections of which quickly remove the surplus material, consisting usually of fibrous material produced by disintegration of the leather, lining and toe box, together with cementitious 75 material which clings to the shoe and with which the fibrous material is more or less impregnated. The shoe is moved axially of the shell to cause all portions of the projecting surplus material to be subjected to the 80 action of the teeth. The removed material passes readily through the large openings in front of the projections and immediately engages, or is engaged by, the scraper 28 by which it is knocked loose from the shell, if it tends to adhere, and, by reason of the 85 inclination of the scraper to the axis of the shell, is moved toward the open end of the shell and discharged therefrom.

Having thus described my invention, what 90 I claim as new and desire to secure by Letters Patent of the United States is:

1. An abrading tool for removing surplus fibrous and cementitious material from the bottoms of boots and shoes prior to the 100 attachment of the outsoles comprising a hollow, cylindrical shell having projections thereon arranged in lines parallel to the axis of the shell, each projection being substantially quarter-spherical in form and having 105 a square scraping edge lying in a radial plane of the shell, the shell having an opening adjacent to each scraping edge no dimension of which is substantially less than the length of the edge so that lumps of sticky 110 material detached from the shoe bottom by said edge will find free passage into the interior of the shell.

2. A machine for removing surplus material from boots or shoes or parts thereof, comprising a rotary, perforated, toothed shell and a scraper plate within the shell arranged to loosen material adhering to the inner surface of the shell.

3. A machine for removing surplus material from boots or shoes or parts thereof, comprising a hollow, cylindrical shell having perforations therein and stock-removing projections formed on the shell, means for rotating the shell about its axis, and a scraper supported at the axis of the shell and having an edge adjacent to the interior surface of the shell.

4. A machine for removing surplus material from boots and shoes or parts thereof,

comprising a hollow, cylindrical shell having perforations therein and stock-removing projections formed on the shell, means for rotating the shell about its axis, and a 5 scraper supported at the axis of the shell and having an edge adjacent to the interior surface of the shell and at an angle to the axis of the shell to cause material removed from the interior surface of the shell by the 10 scraper to be transferred axially of the shell.

5. A machine for removing surplus material from the bottoms of boots or shoes comprising, in combination, a shell having 15 stock-removing projections and perforations adjacent to the projections to admit the removed material to the interior of the shell, means for rotating the shell, and means adjacent to the interior surface of the shell, 20 and between which and the shell there is relative movement, for loosening removed material which tends to cling to the interior of the shell.

6. A machine for removing from the bottoms of boots or shoes the excess of overlasted material at the toe portion thereof, 25 including upper material and toe box wax, comprising, in combination, a rotating shell having stock-removing projections and perforations for admitting the removed material to the interior of the shell, and a scraper having an edge lying adjacent to the inner surface of the shell to remove the upper material and wax which pass through 30 the perforations.

7. A machine for removing surplus material from boots or shoes or parts thereof, comprising a supporting shaft, a rotary sleeve on the shaft, a cylindrical shell having 40 an open end and a wall at its opposite end secured to said sleeve, teeth on the shell adjacent to perforations in the shell, and a blade mounted on the shaft and having an edge adjacent to the inner surface of the 45 cylindrical shell to loosen material clinging to the interior of the shell.

8. A machine for removing surplus material from the bottoms of boots and shoes,

comprising a shaft, a sleeve on the shaft, means for rotating the sleeve, a hollow shell 50 secured to said sleeve and having projections and perforations and an open end, a scraper blade having one edge secured to said shaft and the opposite edge adjacent to the interior surface of the shell and inclined to 55 the axis of the shell, and means for rotating the shaft and scraper to cause transfer of the material scraped from the shell toward the open end thereof by the inclined blade.

9. A machine for removing surplus material from the bottoms of boots and shoes, comprising a shaft, a sleeve on the shaft, means for rotating the sleeve, a hollow shell 60 secured to said sleeve and having abrading projections and perforations and an open 65 end, a scraper blade having one edge secured to said shaft and its opposite edge adjacent to the interior of the shell and inclined to the axis of the shaft, and means to rotate the blade to cause it to remove material from 70 the interior of the shell and create a current of air inwardly through the perforations of the shell and outwardly through the open end of the shell.

10. A machine for removing surplus material from the bottoms of boots or shoes, 75 comprising a hollow shell having projections and perforations, a scraper within the shell for removing material clinging to the interior surface thereof, means for rotating 80 the shell in one direction, and means for rotating the scraper in the opposite direction.

11. A machine for removing surplus material from the bottoms of boots or shoes, comprising a shaft, a sleeve on the shaft, 85 means for rotating the sleeve, a hollow cylindrical shell secured to said sleeve and having projections and perforations, a scraper secured to said shaft and arranged to remove material from the interior of the 90 shell, and means for rotating the shaft and scraper in a direction opposite to the direction of rotation of the sleeve and shell.

In testimony whereof I have signed my name to this specification.

ROBERT P. FRYE.
